DISPLAY COUNTER

Robert Whitsett, Detroit, Mich., assignor to The
Gratiot Fixture & Supply Company, Detroit,
Mich., a corporation of Michigan

Application April 29, 1938, Serial No. 205,041

7 Claims. (Cl. 62—89.5)

The invention relates to a display counter and more particularly to that type of counter which is provided with refrigerating coils.

Recently with the development of mechanical refrigeration, display counters for meats and other perishable goods have been equipped with cooling coils which are furnished with a refrigerant from a compressor which is located either in the base of the counter or on the floor below. These coils are located at the top and bottom of the counter and the bottom coils are then usually covered with removable porcelain trays upon which the perishable goods are displayed. Drip pans have been provided below the coils to catch the condensate and other refuse which falls through the coils. Much difficulty has been experienced in cleaning these drip pans or the panels upon which they rest since, in order to do so, it has been necessary to work through or under the coils with long brushes provided therefor. This has proved unsatisfactory not only because such a cleaning operation is time consuming but, it is also almost impossible to provide a sanitary case with such an arrangement. Furthermore, it is usually considered good practice to paint these cases, once or twice a year and in order to do this, it has been necessary to turn off the refrigerating compressors, drain the coils, and disconnect them to permit removal. This means an interruption of service which is undesirable.

In some cases a movable collecting pan has been utilized, it being so arranged that the collecting pan could be lowered into the lower portion of the case to be cleaned. This is impossible if a permanent partition is desired between the upper and lower portions of the case and the removable pan also requires that all the objects be removed from the lower portion before the pan can be cleaned.

The present invention contemplates a display counter which is so designed that the above disadvantages have been removed.

It is an object of the present invention to provide a cooling coil for a display counter which is so connected to the supply conduits of the compressor that the coil may be moved to a position exposing the bottom of the display case so that it may be readily cleaned or painted, thereby insuring a sanitary case at all times.

A further object of the invention is to provide a coil which may be moved without the necessity of being disconnected.

Other objects and features of the invention have to do with details of construction and de-

sign, including a novel means of mounting the coil, as will be set forth in the following description and claims.

Certain modifications of the invention are illustrated for purposes of exemplification in the following drawing:

Fig. 1 illustrates a plan view of a horizontal section of a display counter.

Figs. 2 and 3 are vertical sections of the counter, Fig. 2 taken on lines 2—2 of Fig. 1, showing the movable coil in various positions.

Fig. 4 is a detail cross section of a movable pipe joint which may be used with the invention.

Fig. 5 is a diagrammatic plan view of a modified form of coil mounting.

The display counter illustrated herein is constructed in the same general manner as cooling display counters of standard construction. Consequently, the details of the construction of the counter itself will not be dwelt upon. The counter consists essentially of a base 6, a front wall 7, a top 8, a sloping window 9 between the front wall 7 and the top 8, and a back 10 between the base and the top. The back is provided with closure members 11 and 12. Ends 13 and 14 are provided for the cabinet. Each of the walls of the cabinet are suitably insulated against heat in accordance with well known constructions and the windows likewise, are provided with double panes to further insulate the cabinet. Between the front wall 7 and the back 10 is located a transverse collecting pan 15 which is mounted at a slight angle to the horizontal so that it will drain readily.

Extending longitudinally throughout the cabinet and above the collecting pan 15 is a coil 16 which, in the present modification, is formed of a series of longitudinally extending parallel conduit members, looped at the ends so that a substantially rectangular area is enclosed by the entire coil (Fig. 1). An outlet end of the coil is indicated at 17 and an inlet end is indicated at 18. Each of the conduits making up the coil extend through transverse bars 19 and 20 which are hinged to the front wall 7 at 21 and which rest, at the other ends, on a portion of the back 10a.

At the end 13 of Fig. 1 are shown a supply pipe 22 and a return pipe 23. At the ends of these pipes and directly adjacent the coil 16 are mounted fluid-tight, pivoted joints 24. Between these joints 24 and the openings 17 and 18 of the coil are flexible connecting hoses 25 and 26. A modification of the joint 24 is shown in Fig. 4.

The fluid-tight joint is provided by forming flanges 27 on each of the joining or abutting pipe

ends. Nuts 28 are provided with a threaded end which engages an intermediate coupling piece 29. Packing washers 30 are placed between the nuts 28 and the flanges 27. Other types of joints may, 5 of course, be used, as long as they permit the movement of the coil.

It will be seen that if the coil 16 is in its normal position, as shown in Fig. 2, access may be had to the collecting pan or drip pan 15 only 10 through the various conduits making up the coil 16. However, with the pivoted mounting which I have shown and, with the flexible connections between the coil and the supply and return pipes 22 and 23, it is possible to lift the coil 16 15 to the position shown in Fig. 3 where it is substantially parallel with the sloping window. In this position the coil may be fastened by a hook 31 and it will be seen that the collecting pan 15 may now be easily cleaned or painted as desired. 20 While I have shown only a collecting pan 15 between the upper and lower storage chambers of the display case, it is quite possible that a permanent partition might be located directly beneath the collecting pan 15 in case the lower 25 portion of the display counter is not to be cooled.

In Fig. 5, I have shown a slightly modified form of coil in which the inlet and outlet ends of the coil also furnish the pivotal support for the front edge. In this modification the supply 30 pipe 22 is located in one end of the counter and the return pipe 23 is located at the other end. Pivoted joints 24 are located at the ends of these supply pipes on a horizontal axis. The inlet end of the coil 16 is brought down along the end of 35 the coil as at 32 and is turned so that it enters the pivoted joint 24 on a horizontal axis extending longitudinally of the case. This axis is in alignment with the axis of the pivotal joint 24 at the other end of the case so that the front edge 40 of the coil is supported by the pipes 22 and 23 and the entire frame formed by the coil may be pivoted on the joints 24. With this modification it is not necessary to provide the flexible hoses 25 and 26 as in Fig. 1.

45 In case a cooling coil is also located in the top of the case it is within the contemplation of the present invention to have the top coil, as well as the lower coil, connected to the same supply and return pipes as long as the connections of the 50 lower coil are such that it may be moved as described. It will be seen that if an expansion valve is used in connection with a thermal bulb mounted on the coil, a flexible connection may be provided therefor.

55 What I claim is:

1. In a refrigeration display counter, a casing having a base, a vertical front wall, a top, a sloping front window between the front wall and top, a rear wall extending between the base and top, 60 and having lower and upper openings and closures therefor, a transverse substantially horizontal cooling coil in said casing having inlet and outlet openings, supply and return pipes for refrigerating fluid located in said casing, means 65 for movably mounting said coil in said casing, and flexible means connecting said coil openings respectively to said supply and return pipes whereby said coil may be moved from its transverse, substantially horizontal position to an inclined position substantially parallel with said sloping front window.

70 2. In a refrigeration display counter, a casing having a base, a top, a front wall and rear wall extending between the base and the top, the rear wall having openings and closures therefor, a 75

cooling coil in said casing for receiving meats and the like, said coil comprising a series of conduits for circulating a cooling medium, said coil having inlet and outlet openings, supply and return pipes for cooling medium, means for movably mounting said coil in said casing, and means joining said inlet and outlet openings respectively with said supply and return pipes whereby said coil may be moved from a normal operative position to permit cleaning of said case beneath said coil. 10

3. In a refrigerating cabinet, a substantially flat cooling coil having inlet and outlet openings and adapted to serve as a support for food products to be stored in said cabinet, supply and return pipes for a cooling medium, means for movably mounting said coil in a substantially horizontal position between walls of said cabinet, and flexible joining means connecting said inlet and outlet openings respectively with said supply and return pipes whereby said coil may be moved within said cabinet to permit cleaning thereunder. 15

4. In a refrigerating cabinet, a substantially flat cooling coil having inlet and outlet openings and adapted to serve as a support for food products to be stored in said cabinet, supply and return pipes for a cooling medium, means for movably mounting said coil in a substantially horizontal position between walls of said cabinet, 20 and means joining said inlet and outlet openings respectively with said supply and return pipes comprising a pivoted, fluid tight joint and a length of flexible tubing whereby said coil may be moved within said cabinet to permit cleaning 25 thereunder.

5. In a display counter, a casing having a base, a vertical front wall, a sloping front window between the front wall and top, a rear wall extending between the base and top and having lower and upper openings and closures therefor, a transverse cooling coil in said casing for receiving meats and the like, said coil being formed of a series of substantially parallel conduits and having inlet and outlet openings, said coil being normally disposed in a position substantially between said front wall and said rear wall, means for pivotally connecting the front portion of said coil to said front wall, a collecting pan disposed below said coil when in its normal position, supply and return conduits for a cooling medium, and means for connecting said openings of said coil respectively to said supply and return conduits comprising flexible coupling means whereby said coil may be moved from its normal position to an inclined position substantially parallel with said sloping window to permit access to said collecting pan beneath said coil. 40

6. In a display counter, a casing having a base, a top, a front wall and rear wall extending between said base and top, the rear wall having openings and closures therefor, a transverse cooling coil in said casing formed of a series of conduits, said coil being normally disposed in a position substantially between said front wall and said rear wall, inlet and outlet pipes on said coil, one extending from each end of said coil and substantially in alignment, a pipe located at each end of said casing adapted to serve, respectively, as supply and return pipes for cooling medium, and pivotal couplings connecting said inlet and outlet pipes on said coil respectively with said supply and return pipes in said casing whereby said coil may be moved from its normal 45 position to an inclined position substantially parallel with said sloping window to permit access to said collecting pan beneath said coil. 50

position to permit access to the portion of said casing normally below said coil.

7. In a display counter, a casing having a base, a top, end walls and a front wall and rear wall extending between said base and top, the rear wall having openings and closures therefor, a transverse cooling coil in said casing formed of a series of conduits arranged to include a substantially rectangular area within said casing and normally disposed in a position substantially between said front wall and said rear wall, a collecting pan disposed below said coil in normal position, and conduits connected to each end of

said coil and extending in substantial alignment with each other and longitudinally of said case, pipes located at each end of said casing adapted to serve, respectively, as supply and return pipes for cooling medium, and pivotal coupling means connecting said end conduits on said coil with said supply and return pipes, respectively, whereby one edge of said coil is pivotally supported thereon such that said coil may be pivoted from its normal position to permit access to the portion of said casing normally below said coil. 5 10
